UNITED STATES PATENT OFFICE.

BERT G. RENTZ, OF WELLS, MINNESOTA.

VENDING GAME APPARATUS.

Application filed August 15, 1927. Serial No. 212,896.

My invention has for its object to provide a vending game apparatus intended for general use, such as the embodiment of a ball-throwing apparatus in a vending machine.

5 The invention, as illustrated, includes basket-ball game apparatus embodied in a vending machine for dispensing spherical pieces of gum.

To the above end, generally stated, the invention consists of the novel devices and combinations of devices hereinafter described and defined in the claims.

In the accompanying drawings, which illustrate the invention, like characters indicate like parts throughout the several views.

Referring to the drawings:

Fig. 1 is a view in longitudinal central vertical section, with some parts shown in different positions by means of broken lines;

20 Fig. 2 is a perspective view of the secondary bottom partition and the parts carried thereby removed from the machine;

Fig. 3 is a bottom plan view of the same;

25 Fig. 4 is a fragmentary view of the parts shown in Fig. 3, with some parts removed;

Fig. 5 is a detail view principally in section taken on the line 5—5 of Fig. 2;

30 Fig. 6 is a fragmentary rear end view of the machine with some parts sectioned on the line 6—6 of Fig. 1;

Fig. 7 is a fragmentary detail view with some parts sectioned on the line 7—7 of Fig. 6;

35 Fig. 8 is a view corresponding to Fig. 7 with the exception that the ejector has been operated to release the ball of gum; and

Fig. 9 is a fragmentary detail view with some parts sectioned on the line 9—9 of Fig. 1.

40 The numeral 10 indicates a casing having main and secondary bottoms 11 and 12, respectively, spaced the latter above the former to afford a combined mechanism and coin compartment 13. Said casing 10 is also provided with a transverse vertical partition 14 which extends from the secondary bottom 12 to the top of the casing 10 and divides said casing above the compartment 13 into a relatively small storage compartment 15 at 45 the back of the casing 10 and a relatively large compartment 16 at the front thereof for a basketball game. A door 17 in the back of the casing 10 affords access to the compartment 13 and a door 18 at the top of said casing affords access to the storage compartment 16. Each door 17—18 is held in place

by dowel pins that take the place of hinges and a key-actuated lock.

The top of the casing 10 covering the compartment 16 is rearwardly inclined and has 60 a large glass panel 19, and large glass panels 20 form portions of the sides of the casing 10 so that the interior of the compartment 16 may be viewed through said panels 19 and 20. A window 21, having a transparent 65 pane, is formed in the compartment 14 and through which the contents of the storage compartment 15 may be seen.

The machine illustrated is designed for vending spherical pieces of gum *x*, with 70 which the storage compartment 15 is filled, through the door 18. The secondary bottom 12 is removably secured in the casing 10 by pairs of pins 22 mounted in longitudinal grooves 23 on the sides of the casing 10. The 75 entire back of the casing 10 is removably secured in position so that the same cannot be tampered with but at the same time may be removed so that the secondary bottom 12 and partition 14, which is secured thereto, 80 as shown in Fig. 2, may be removed from the casing 10 with all parts carried thereby. The partition is removably secured to the secondary bottom 12 by having its lower end seated in a transverse groove in said bottom 85 and when the casing 10 is held against removal therefrom by the side and top thereof.

The pieces of gum *x* are removed from the compartment 15 one at a time through a passage 24 in an agitator slide 25 mounted in a 90 way formed in the secondary bottom 12 for movement longitudinally of the machine. A curved sheet metal plate 26 secured in the bottom of the compartment 15 is arranged to cause the balls of gum *x* to roll to the center 95 of said compartment where they will enter the passage 24 one at a time, as shown in Figs. 7 and 8.

The plate 26 holds the agitator slide 25 against lifting movement in its way and has a large central aperture in the field of which the passage 24 is positioned during the various movements of the agitator slide 25. Secured to the agitator slide 25 are a plurality of upstanding agitator pins 27 which work 105 within the aperture in the plate 26 and move the ball of gum *x* during the movement of the agitator slide 25 and thereby cause one thereof to enter the passage 24.

Working in the compartment 13, longitudinally of the machine is an ejector 28 in the form of a slide attached to the under side of

the secondary bottom 12 by a pair of washer-equipped screws 29 which extend through longitudinal slots 30 in said ejector, see Fig. 3. This ejector 28 can only be operated by the insertion of a coin in the machine, as will presently appear. The agitator slide 25 works on the upper surface of the ejector slide 28 and is intermittently operated thereby by a pair of front and rear pins 31 and 32, respectively, on said ejector slide. The pin 31 is arranged to work in a groove 33 in the under side of the secondary bottom 12 and the way for the agitator slide 25, and the pin 32 works in a slot 34 on the bottom of the agitator slide 25 which extends forward of the rear end thereof. During the forward movement of the ejector slide 28, the pin 32 engages the agitator slide 25 at the inner end of the slot 34 and carries the same forward. During the return movement of the ejector slide 28 its pin 31 engages the front end of the agitator slide 25 and returns the same to normal position.

Formed in the ejector slide 28 is a gum passage 35 which is in registration with the passage 24. Underlying the ejector slide 28 and secured to the casing 10 is a deck 36 on which the piece of gum α in the passage 35 rests, and the piece of gum in the passage 24 rests on the piece of gum in said passage 35, see Fig. 7. Formed in the deck 36, forward of the passage 35, is a gum escape passage 37. During the forward movement of the ejector slide 28, the same moves under the piece of gum in the passage 24 and cuts off the escape thereof and moves the piece of gum in the passage 35 forward therewith on the deck 36 and when stopped, the passage 35 is in registration with the escape passage 37 so that the piece of gum in the passage 35 may escape therethrough, as shown in Fig. 8.

Underlying the escape passage 37 is an inclined runway 38 which extends to the front of the casing 10 and aligned therewith is a gum discharge passage 39 formed in the front of the casing 10, see Fig. 9. A partition plate 40 in the compartment 13 closes the runway 38 thereto, both at the side and rear, see Figs. 6 and 8. The main bottom 11 extends forward of the casing 10 and has secured thereto, as shown in Fig. 9, a pair of upstanding pins 41 which stop the piece of gum α as it rolls through the discharge passage 39, as indicated by broken lines, where the same may be easily picked up by the operator of the machine.

For operating the ejector slide 28 and then resetting the same, there is provided the following connections, which include an operating slide 42 for the ejector 28 mounted in a deep channel 43 formed in the right-hand edge of said slide for free sliding movement longitudinally thereof. Rearward movement of the operating slide 42 in its channel 43 is limited by a stop pin 44 secured to the

ejector slide 28, extends transversely through its channel 43 and is arranged to be engaged by a stop shoulder 45 on said operating slide. Forward movement is imparted to the operating slide 42 by a rod 46 comprising inner and outer sections connected by a flexible joint 47. The rear end of the rod 46 is flexibly attached to the operating slide 42 by having its rear end portion bent laterally at 48 and laid in a transverse notch 49 in said slide. The forward end of the rear section of the rod 46 is arranged to engage the inner face of the front of the casing 10 to limit the forward movement of the operating slide 42. The forward section of the rod 46 works through a hole in the front wall of the casing 10, and applied to its outer end is a knob 50 by which said rod may be operated. A coiled spring 51, attached to the rod 46 at its laterally bent end 48 and anchored to the pin 52 secured in the secondary bottom 12, yieldingly holds the operating slide 42 retracted.

Normally, the operating slide 42 is free to be moved forward in respect to the ejector slide 28 by drawing outward on the knob 50 and it is also free for retracting movement in respect to the ejector slide 28 under the action of the spring 51.

A coin γ is required to connect the ejector slide 28 to the operating slide 42 when inserted into a transverse notch 53 in the ejector slide 28 just forward of the front end of the operating slide 42 when in its retracted position, see Fig. 1. The coin γ is inserted into the notch 53 through a coin passage, not shown, in the top of the casing 10 and a coin delivery chute 54 formed in the right-hand edge of the partition 14 and the secondary bottom 12, see Fig. 2. Secured to the casing 40 and underlying the notch 53 is a stop plate 55 on which the coin γ rests when in the notch 53.

The spring 51 normally and yieldingly holds the operating slide 42 retracted and which slide in turn holds the ejector slide 28 retracted by the engagement of its shoulder 45 with the pin 44 on said ejector slide. A stop pin 12' on the secondary bottom 12 is arranged to be engaged by the shoulder 28' to limit the retracting movement of the ejector slide 28 and hence the operating slide 42. In the retracted position of the ejector slide 28, its passage 35 is aligned with the passage 24 and its coin notch 53 is aligned with the coin chute 54. As previously stated, the front end of the rear section of the rod 46 engages the casing 10 as a stop to limit the projecting movement of the ejector slide 28 and position the ejector slide 28 with its passage 35 aligned with the discharge passage 37.

To operate the vending machine to secure one of the balls of gum α , the coin γ is deposited in the coin chute 54 and directed thereby into the coin notch 53 in which it rests on the stop plate 55. The operator then takes hold

of the knob 50 and draws the same outward to project the operating slide 42. The initial forward movement of the operating bar 42 will engage the coin γ and clamp the same 5 against the ejector slide 28 and thereby connect said slides for common forward movement. During this movement of the ejector slide 28 the gum α in the passage 35 is carried forward on the deck 37 until said passage 10 is aligned with the discharge passage 37 and at which time the gum α drops through said passage 37 onto the runway 38 on which it rolls forward through the discharge passage 39 onto the main bottom 11 where it is stopped 15 by the pins 31 and positioned so that the operator may take the same.

When the operator releases the knob 50, the spring 51 retracts the operating slide 42, thus releasing the coin γ , which drops into 20 the coin compartment 13. After the initial retracting movement of the clamping bar 42 its shoulder 45 engages the pin 44 and thereby retracts the ejector slide 28, as previously described. The coin γ in the compartment 13 25 may be removed by opening the door 17 after the same is released by the use of a proper key.

Referring now to the game apparatus for playing basketball, the numeral 56 indicates a basket mounted on the partition 14 within 30 the compartment 16. This basket 56 is carried by the heavy wire 57 fitted around the top of said basket and provided with a pair of depending legs 58 slidably mounted in staple-like keepers 59 on the partition 14. 35 The basket 56 is normally gravity-held in its lowermost position, as shown by full lines in Fig. 1.

Back of the basket 56 is a pocket 60 in the partition 14. The back of the basket 56 is 40 opened as well as its bottom, with the exception of an inturned lip 61 which holds the ball z , as shown by full lines in Fig. 1. By raising the basket, as indicated by broken lines in Fig. 1, the ball z will be released and dropped 45 therefrom.

To throw the ball into the basket 56, there is provided a catapult comprising an inclined cylinder 62 mounted on the front of the casting 10 and having a co-operating piston-like 50 member 63 to which is attached an operating rod 64 that works through a hole in the cylinder head 65. The outer end portion of the operating rod 64 is bent to form a finger-piece 66 by which said rod may be held. The inner 55 end of the operating rod 64 is bent laterally to form a finger 67 seated in a recess in the outer face of the piston-like member 63 so that the same is flush therewith. This finger 67 works in a slot 68 in the cylinder 62 and 60 limits the travel of the piston 63 in both directions. Encircling the operating rod 64 is a coiled spring 69 compressed between the piston-like member 63 on the cylinder head 65 and normally holds said member projected. 65 To place the ball z in the inner end of the

cylinder 62 so that the same bears against the piston-like member 63, as shown by broken lines in Fig. 1, there is mounted in the compartment 16 a channel-like runway 70. This runway 70 has its front end hinged at 71 and 70 is normally gravity-held in an inclined position, as shown by full lines in Fig. 1, so that the ball z cannot roll into the cylinder 62. To raise the runway 70 into its dotted line 75 position, as shown in Fig. 1, at the time the ejector slide 28 is operated, there is provided a bell-crank 72 hinged at 73 to the secondary bottom 12 with one of its arms extended under the runway 70 for action thereon and with its other end extended downward through 80 aligned slots 74 in the secondary bottom 12 and ejector slide 28. During the ejector movement of the ejector slide 28, said slide at the rear end of its slot 74 engages the depending arm of the bell-crank 72 and operates the same to raise the runway 70, as shown by 85 broken lines in Fig. 1. A cross pin in the ejector slide 28 is arranged to engage the depending arm of the bell-crank 72 during the return movement of the ejector slide 28 and thereby move said bell-crank from under the runway 70 and permit the same to return by 90 gravity to its normal position.

During the lifting movement of the runway 70, its free or inner end engages a depending extension 76 on one of the legs 58 and thereby lifts the basket 56, as shown by broken lines in Fig. 1, to release the ball z and permit the same to drop onto the raised runway 70 and be conveyed thereby into the cylinder 62, and held as shown by broken lines in Fig. 1. Before the ball z can be thrown into the basket 56 it is necessary for the operator to release the knob 50 to permit the retracting movement of the operating slide 42 and all parts associated so that the runway 70 will return to normal position under the action of gravity and thereby release the basket 56 and permit the same to return to normal 100 position in a like manner.

To throw the ball z , the piston-like member 63 is retracted by drawing outward on the finger-piece 66 and then released to attempt to throw the ball into the basket 56. If the ball is thrown into the basket 56, the same will be held, as shown by full lines in Fig. 1. If the ball does not enter the basket 56 it drops onto the runway 70 and is held thereby at the partition 14 so that the next time the runway 70 is raised, said ball will be conveyed thereby into the cylinder 62. It will thus be seen that it will be impossible to get the ball z into the cylinder 62 without operating the machine by means of a deposit coin in order to get one of the balls of gum α .

The skill with which the ball z is thrown depends on the amount of tension placed on the spring 69 by the retraction of the piston-like members 63. A wearing plate 77 is secured to the upper end portion of the run-

way 70 for the leg extension 76 when the runway 70 is operated to lift the basket 56 and release the ball 2 and position said runway to cause the ball 2 to be deposited in the cylinder 62.

What I claim is:

1. In combination with the ejecting mechanism of a vending machine, ball-throwing mechanism, a ball, a runway normally held to cause the ball to roll away from the ball-throwing mechanism, and means operated by the ejecting mechanism for positioning the runway to cause the ball to roll into a position to be acted on by the ball-throwing mechanism.
2. The structure defined in claim 1 in further combination with a basket positioned to catch the ball when thrown by the ball-throwing mechanism, and means operated by the ejecting mechanism for causing the basket to release the ball to the runway when said runway is positioned to return the ball to the ball-throwing mechanism.
3. In combination with the ejecting mechanism of a vending machine, ball-throwing mechanism, a ball, a runway normally held to cause the ball to roll away from the ball-throwing mechanism, a basket normally positioned to catch the ball when thrown by the ball-throwing mechanism, and means operated by the ejecting mechanism during its ejecting action to position the runway to cause the ball to roll into a position to be acted on by the ball-throwing mechanism and move the basket into a position to release the ball to the runway and prevent the ball from being again thrown therein, said basket and runway being arranged to return to normal positions during the resetting of the ejecting mechanism.
4. A vending machine having operating connections, an ejector arranged to be actuated by said connections when connected thereto by a deposited coin, and automatic means for resetting the operating connections when released and causing the release of the

deposited coin and the resetting of the ejector, in combination with ball-throwing apparatus, a ball, and means operated by the ejector during its ejecting action for positioning the ball to be acted on by the ball-throwing apparatus and rendered inoperative by the resetting of the ejector by the operating connections, when released.

5. A vending machine having operating connections, an ejector arranged to be actuated by said connections when connected thereto by a deposited coin, and automatic means for resetting the operating connections when released and causing the release of a deposited coin and the resetting of the ejector, in combination with ball-throwing apparatus, a ball, a ball runway normally positioned to cause the ball to roll away from the ball-throwing apparatus, and means operated by the ejector to position the runway to cause the ball to be delivered to the ball-throwing apparatus and permit the return of the runway to normal position when the operating connections are released.

6. A vending machine having operating connections, an ejector arranged to be actuated by said connections when connected thereto by a deposited coin, and automatic means for resetting the operating connections when released to cause the release of the deposited coin and the resetting of the ejector, in combination with a ball-throwing apparatus, a ball, a basket positioned to catch the ball when thrown by the ball-throwing mechanism, and means operated by the ejector during its ejecting action to move the basket to release the ball to the runway and prevent the same from again being thrown therein and for moving said runway into a position to cause the ball to roll into a position to be acted on by the ball-throwing mechanism, said runway and basket being arranged to return to normal positions during the resetting of the operating connections and the ejector.

In testimony whereof I affix my signature.

BERT G. RENTZ.
